UNITED STATES PATENT OFFICE.

HUGH DUFFEY AND JESSE VANDENBURGH, OF CORTLAND, NEW YORK.

HUB-BORING MACHINE.

SPECIFICATION forming part of Letters Patent No. 244,439, dated July 19, 1881.

Application filed March 31, 1881. (No model.)

To all whom it may concern:

Be it known that we, HUGH DUFFEY and JESSE VANDENBURGH, citizens of the United States, residing at Cortland, in the county of Cortland and State of New York, have invented 5 certain new and useful Improvements in Hub-Boring Machinery; and we do hereby declare the following to be a full, clear, and exact description of the invention, such as will 10 enable others skilled in the art to which it appertains to make and use the same, reference being had to the accompanying drawings, and to the letters or figures of reference marked thereon, which form a part of this specification. 15

In the drawings, Figure 1 represents a side view of the apparatus and its parts. Fig. 2 represents a section of the cutter. Fig. 3 represents a side elevation of the front of the device 20 for clamping and securing the wheel while being bored. Fig. 4 represents a back elevation of said device. Fig. 5 represents a section of the cutter. Fig. 6 represents another section of the cutter.

Like letters of several figures indicate same parts. 25

The object and purpose of our invention or improvements are to bore out the hubs of wheels used on wagons or vehicles, so that the iron 30 boxes can be easily put in the hubs accurately and uniformly; also, to so bore the hubs very quickly and readily by machinery, dispensing with hand-work.

Our invention consists in the apparatus or devices hereinafter described and herein shown, whereby we accomplish the said object and purpose; also, in the arrangement and combination of the parts composing the apparatus; 35 also, in the internal air-blast, preventing interference from the detritus of the boring instruments.

In said drawings, A and B represent two similar standards securely bolted to a base, as shown.

C, C', C², and C³ are journals in said standards for shafts D and E to revolve in.

F and F' are pulleys on shafts, to which motion is communicated.

G and G' are levers or slide-bars for sliding 40 the shafts D and E forward.

H represents the device or apparatus for holding the wheel while the hub is being bored.

The crank I, with its rod, having right and left screws J and J', brings the shoulders K and K' together, and centers and holds the 55 wheel. The hub being brought in opening L, in accurate position to be bored, H is securely held in position by being firmly bolted, as shown. The shaft D is hollow for a blast of air to pass through it. 60

M is a flexible tube for conveying the air to D from the fan or blast.

N represents the cutter, which consists of the instrument shown in Fig. 2, having knives or cutting-instruments a a placed on its surface, 65 as shown. These cutters are shown better in Figs. 5 and 6. The chips and shavings pass into N, and are blown out by the blast. There are cutters on shoulder b.

The operation of the machinery is as follows: 70 The wheel is brought into position and held by the device H. Then by lever G' the auger or bit O is brought forward and forced to bore through the hub, making a hole of proper diameter. Then by lever G' the auger O is pulled 75 back. Then by lever G the cutter N is brought forward and passed into the hole in the hub made by O, giving to said hole its shape. The chips and shavings pass within the cutter N, and are driven out by the air-blast; also, the 80 shavings and chips formed by the auger O are driven out of the grooves of said auger O by said blast. The wheel is then released by I, and the hole in the hub is of the correct form to receive the box. By the internal blast all 85 clogging and trouble from chips and shavings is avoided, and the cutting-instruments are kept cool.

What we claim is—

1. In a hub-machine, the inclined cutter or 90 reamer, as shown, having a series of knives upon the sides thereof, and provided with a central longitudinal tube having flexible connection with an air-blast, said blast being adapted to blow the chips and cuttings away from 95 the parts to prevent clogging, as set forth.

2. The inclined cutter N, having hollow center, combined with an air-blast and flexible connections, with a primary borer, O, and intermediate clamp, the said blast serving not 100

only to remove the chips from the cutter N, but also to remove the same from the worm-groove in the borer simultaneously, as specified.

5. In a hub-boring machine, the tapering cylindrical reamer N, having central longitudinal aperture P, the plane knives upon the surface, and passages leading therefrom to the interior to allow the chips to pass within the current 10 of the air-blast and be blown out, substantially as and for the purposes set forth.

4. The combination of the holder H, right and left screw J J', the clamp L, with the primary borer E O, the finishing-cutter D N, 15 the levers G G', and the air-blast connections, all combined and arranged to serve as and for the purposes set forth.

5. In a hub-boring machine, the combination and arrangement of the shafts D and E, with their respective cutters N and O, the 20 clamping device, the levers G and G', and the flexible blast-tube M, all arranged, combined, and used substantially as and for the purposes specified.

In testimony whereof we affix our signatures 25 in presence of two witnesses.

HUGH DUFFEY.

JESSE VANDENBURGH.
